(57) **CLAIM**

The ornamental design for a display screen with graphical user interface, as shown and described.

DESCRIPTION

The patent file contains at least one drawing executed in color. Copies of the patent file with color drawing(s) will be provided by the Patent Office upon request and payment of the necessary fee.

FIG. 1 is a front view of a display screen with graphical user interface showing our new design;

FIG. 2 is another embodiment thereof;

FIG. 3 is another embodiment thereof; and,

FIG. 4 is another embodiment thereof.

The dot-dash line representations of the display screen in the figures, and the dash line representations in FIGS. 3 and 4, form no part of the claimed design.

**1 Claim, 4 Drawing Sheets
(2 of 4 Drawing Sheet(s) Filed in Color)**
